UNITED STATES PATENT OFFICE

164,331

RADIO RECEIVER CABINET

Oscar Schliom, Montreal, Quebec, Canada

Application April 21, 1951, Serial No. 14,907

Term of patent 3½ years

(CL. D56—4)

To all whom it may concern:

Be it known that I, Oscar Schliom, a Canadian citizen, residing at 363 Sherbrooke Street West, city of Montreal, Province of Quebec, Canada, have invented a new, original and ornamental design for a Radio Receiver Cabinet, of which the following is a specification, reference being had to the accompanying drawing, forming part thereof.

The single figure shown is a perspective view of the radio receiver cabinet embodying my new design.

The rear portion of the cabinet is similar to the front portion shown except for the grille and dial.

I claim:

The ornamental design for a radio receiver cabinet, as shown and described.

OSCAR SCHLIOM.
